(57) **CLAIM**

The ornamental design for a level indicator, as shown and described.

DESCRIPTION

FIG. 1 is a top view of an embodiment of the level indicator of Applicants' invention.

FIG. 2 is a left view of an embodiment of the level indicator of Applicants' invention.

FIG. 3 is a right view of an embodiment of the level indicator of Applicants' invention.

FIG. 4 is a bottom view of an embodiment of level indicator of Applicants' invention.

FIG. 5 is a front view of an embodiment of the level indicator of Applicants' invention.

FIG. 6 is a back view of an embodiment of the level indicator of Applicants' invention; and,

FIG. 7 is an isometric view of an embodiment of the level indicator of Applicants' invention.
